UNITED STATES PATENT OFFICE

WILHELM TASCHNER, OF KREFELD, GERMANY

SKEIN-YARN-BEATING MACHINE

Application filed December 1, 1928, Serial No. 323,044, and in Germany June 1, 1927.

Skein-yarn beating machines serve to disentangle the skeins which have been entangled in the dyer's works or otherwise, i. e. to place the several yarn windings parallel. 5
 5 Machines of this type of known construction comprise centrically revolving cylinders adjustable to the skein length and eccentrically mounted cylinders, forming together one pair of cylinders, by means of which the 10 skeins are continually stretched and slackened. In these machines the skeins are stretched continually with the same force without consideration to the degree of entangling. It is however more advantageous, 15 if the operation of such a machine is more similar to the formerly used working by hand, i. e. regulated so that it considers the peculiarity of every individual skein.

Skein-yarn beating machines have further become known, in which the pair of cylinders is composed of two centrically mounted cylinders, the one of which, the carrying cylinder, being driven, the other one, the beating cylinder, being mounted in an oscillatable lever controlled by an eccentric disc. 20 Also these machines work far too positively with regard to the difference of the yarns and their degree of entangling, as on the yarn-skeins shocks of continually uniform 25 strength are exerted in predetermined intervals, but mainly for the reason that the beating cylinder oscillates always at the same amplitude. This presents the great inconvenience that those threads which, owing to 30 the entangling and curling, have a smaller circumference than the normal skein are torn by the first shocks.

In skein-yarn beating machines the one cylinder of a pair of cylinders has been hitherto driven continually so that the skeins circulate when the shocks are carried out. This has proved to be a serious inconvenience. If a circulating skein is stretched by the beating cylinder the threads are mutually 45 shifted in the longitudinal direction as the threads directly in contact with the cylinders advance with regard to the threads farther to the outer side. The friction caused hereby is specially detrimental to artificial silk.

50 In the skein-yarn beating machine accord-

ing to the present invention the skein-cylinder cooperating with the eccentrically mounted beating cylinder is arranged on an adjustable hand lever, balanced by a counter-weight. In this machine the shock is therefore carried out in known manner by the eccentric cylinder mounted in this case on the top, while the strength of the shock and the amplitude of the oscillation are regulated by hand by according adjusting of the lever carrying the lower skein-cylinder. For the elastic securing of the lever for the cylinder carrying the skein in different positions, there is further arranged on the machine frame a shiftably locking ring plate with notches 55 controlled by clamping springs, a spring-controlled bolt of the cylinder lever designed to engage with said notches. This locking of the cylinder lever takes place as soon as the 60 entangled threads have been beaten out up to the full skein circumference. The machine continues then to run without attendance, whereby the threads are laid parallel by the following shocks. By a convenient control mechanism the revolution of the cylinder effecting the circulating of the skein is interrupted during the beating. This can be obtained for instance by arranging the eccentric cylinder loosely on its axle and by making the same strike in the outer dead center 65 position against a brake, which securely holds said cylinder at the moment of the beating and rotates the cylinder then in the direction opposite to the direction of rotation of the 70 crank pin.

75 An embodiment of the invention is shown by way of example in the accompanying drawing in which:—

Fig. 1 is a front elevation and

Fig. 2 a side elevation showing the beating machine.

Figs. 3 to 5 illustrate various positions of one cylinder pair and of one yarn skein and

Figs. 6 to 9 illustrate certain elements of the beating machine.

The eccentric cylinder *a* is loosely mounted on the crank pin *i*, the counter- or skein cylinder *b* being mounted in a lever *c* pivotal at *d* and carrying on its rear end a balancing 100

weight *e* having at its front end a handle *f*. Around the cylinders *a* and *b* the skeins *h* are placed. The crank pin *i* rotates in the direction of the arrow *I*. The cylinder *a* has a collar *k* which is situated in the path of a brake *m* arranged in the extreme dead center.

The operation of the machine is best seen from Figs. 3 to 5. The skeins to be disentangled are placed around the cylinders *a* and *b* as shown in Fig. 3. *g* designates the threads which, owing to entangling and curling, have a less great circumference than the normal skein *h*. Prior to starting the machine the cylinder *b* is lifted by means of its lever *c* so far that also the threads having the shortest circumference are not acted upon by the shocks of the cylinder *a*. The lever *c* is then gradually lowered, whereby the entangled threads are beaten out, through the state shown in Fig. 4, to the full skein circumference as shown in Fig. 5. In this manner the threads are very carefully treated in comparison with the known machines.

Suppose, the cylinder *a* rotates around the crank pin *i*, this rotating will thus be interrupted as soon as the collar *k* strikes against the brake *m*. This takes place at the point at which the cylinder *a* is at the greatest distance from the cylinder *b*, i. e. at the moment when the shock has to be carried out. After passing through the dead centre position the collar *k* circulates on the brake *m* and is thereby turned in the direction of the arrow *II*. The next following shock strikes the skein therefore at another point, but the skein is always at rest during the execution of the shocks.

If the cylinder *b* has arrived in the position shown in Fig. 5 the entangled threads having been beaten out with greatest possible care up to the complete skein circumference, the lever *c* is secured in its position in order that the machine can continue to run without attendance, whereby by further beating the threads are arranged i. e. laid parallel. With this object in view a plate *n* with notches *o* is arranged on the machine frame. As the shocks must however still further be elastic, the plate *n* is yieldably mounted. It is shiftable in a casing *p* and controlled by two springs *q*, the tension of which may be adjusted by means of screws *r*. On the lever *c* a spring-controlled bolt *s* is arranged designed to engage with one of the notches *o*, the lever *f* being thus elastically secured in the desired position. By pressure exerted upon the lever *t*, the bolt *s* is disengaged from the notch *o* with the aid of well known means. Several notches *o* must be provided, as the skeins are of different length.

I claim:

1. A skein-yarn beating machine, compris-

ing in combination with an eccentrically mounted beating cylinder, a skein cylinder co-operating with said beating cylinder, an adjustable hand lever on which said skein cylinder is mounted, and a counter weight 70 for balancing said hand lever.

2. A beating machine as claimed in claim 1, in which the lever carrying the skein cylinder is adapted to be yieldingly secured in its different positions, comprising in combination with the machine frame, a shiftable locking plate having notches arranged on the machine frame, springs controlling the locking plate, and a spring controlled bolt on said skein cylinder lever adapted to engage 80 with one of said notches of said locking plate.

3. A beating machine as specified in claim 1, comprising in combination, a control mechanism for interrupting the rotation of 85 the skein cylinder during beating.

4. A beating machine as specified in claim 1, comprising in combination, a brake against which the eccentric beating cylinder strikes in the extreme dead center position 90 so that it is stopped by said brake and then rotated in opposite direction.

In testimony whereof I affix my signature.

WILHELM TASCHNER.
